UNITED STATES PATENT OFFICE.

JOHN C. STEVENS, OF HARTFORD, CONNECTICUT, ASSIGNOR TO JAMES C. CLOYD, OF GLEN HEAD, NEW YORK.

BUTTON-SETTING MACHINE.

SPECIFICATION forming part of Letters Patent No. 532,833, dated January 22, 1895.

Application filed December 1, 1893. Serial No. 492,415. (No model.)

To all whom it may concern:

Be it known that I, JOHN C. STEVENS, a citizen of the United States, residing at Hartford, in the county of Hartford and State of Connecticut, have invented certain new and useful Improvements in Button-Setting Machines, of which the following is a specification.

This invention relates to machines for attaching buttons to shoes or fabrics by means of malleable metallic fasteners; and it is especially intended as an improvement upon the button-setting machine shown and described in United States Letters Patent No. 381,031, dated April 10, 1888, to which reference may be had.

The object of the invention is to furnish a button-setting machine of improved organization and construction; and especially, to provide an improved fastener containing magazine and devices for feeding the fasteners from the magazine to the driving-mechanism, whereby the fasteners may be inserted, one at a time, through the shoe-upper or fabric and the button-eye, and formed into a hook to hold the button to the fabric; and to so combine the magazine with the other elements that the same may be quickly released from its operative position with relation to the driving-mechanism, swung outward into position to be filled, opened and re-filled without removing the same from the machine and without disassembling the parts thereof, as will be hereinafter more fully described.

In the drawings accompanying and forming a part of this specification, Figure 1 is a front elevation of a button-setting machine embodying my improvements, the supporting-column being broken off. Fig. 2 is a side elevation of the button-setting machine as seen from the right-hand in Fig. 1. Fig. 2^a is a rear view of a portion of the framework of the machine showing the button-feed-wheel shaft detent-catch or locking-device. Fig. 3 is a side elevation of the button-setting machine as seen from the left-hand in Fig. 1. Fig. 4 is a vertical cross-sectional view of the machine in dotted line a—a, Fig. 3, showing the mechanism at the left of said dotted line. Fig. 5 is a plan view of the machine. Fig. 6 is a vertical section of the machine taken

in line b—b, Fig. 1 and showing the mechanism at the left-hand side of said dotted line. Fig. 6^a is an enlarged cross-sectional view taken in dotted line c—c, Fig. 6, showing the presser-slide and driver and guide therefor. Figs. 7 and 8 are full size vertical sectional detail views showing the presser-slide, driver, and actuating mechanism therefor in their two extreme positions. Fig. 9 is a full size horizontal cross-section of the machine taken in dotted line d—d, Fig. 6, looking downward and showing the fastener-containing magazine and fastener feeding device. Fig. 10 is a full size vertical cross-section taken in dotted line e—e, Fig. 9. Fig. 11 is a detail view in plan of a portion of the frame of the machine showing the fastener-magazine swung outward from the frame and in position to be opened for inserting fasteners. Fig. 12 is an end view of the same drawn in projection with Fig. 11. Fig. 13 is a view similar to Fig. 11 showing the magazine swung outward and opened and in position it occupies when being filled with fasteners. Fig. 14 is a side elevation of the same drawn in projection with Fig. 13. Figs. 15, 16 and 17, are detail views in front elevation of a portion of the button-chute and the feed-wheel showing said wheel in three successive stages of its operation in feeding buttons. Figs. 18, 19 and 20, are sectional detail views showing three successive positions of the fastener-driver in its operation of driving and clinching a fastener.

Similar characters designate like parts in all the figures.

The frame of the machine, designated in a general way by A, consists, or may consist of a hollow or skeleton casting substantially as shown and adapted for carrying the several parts of the respective mechanisms, and consists, essentially, of the horizontal base, 2, and the upright, 3, having the button-reservoir, R, at its upper end. As shown in the drawings, the main frame A is bolted to a hollow intermediate frame, A', which in turn is supported upon a column, A². In practice, it may sometimes be desirable to dispense with the column A² and intermediate frame A' and to bolt the main frame A directly upon a table or work-bench. The frame A

has bearings for the vertical presser-slide, S, and is constructed for carrying and pivotally supporting the magazine, M, as will be hereinafter described, and is also provided with 5 bearings for supporting the horizontal shaft which carries the button-feed wheel, F, one of which bearings also forms the head for supporting the die-block, B. The construction of this die-block will be hereinafter fully 10 set forth.

The presser-slide S which is, or may be, of the same general construction as the presser-slide similarly designated in Patent No. 381,031, heretofore referred to, is grooved on 15 its rear face to receive the driver D which is supposed to be of the same construction as the driver described in the aforesaid patent. The upper end of said slide is formed to receive the cap, E, whose back cross-bar, 4', shown most clearly in Figs. 7 and 8, forms 20 the rearward wall of the driver-channel, 4, as more fully described in United States Patent to F. H. Richards, No. 369,260, dated August 30, 1887, to which reference may be 25 had. Said slide is adapted to bear, when in its lowermost position as illustrated in Fig. 7, upon a suitable stop, P, herein shown as a pin secured in the frame of the machine.

As a means for depressing the slide S, in 30 case the same should not descend by its own gravity upon the retractive movement of the driver, the said driver is provided with a projection, 5, which extends into a transverse recess in the slide and is adapted, upon the 35 descent of the driver, to strike the lower wall, 5', of, and carry the slide downward with it, as will be understood by reference to Fig. 8 wherein the driver and slide are shown in contact in dotted lines. The driver 40 D which is and may be of the ribbed construction shown and described in Patent No. 369,260 hereinbefore referred to, is formed at its upper end to pass through the usual driver-channel, as 4, as shown in Fig. 6^a and 45 will be operated by means hereinafter fully described.

The presser-slide S is moved upward by the driver through the medium of a suitable spring. The preferred construction and arrangement of this feature is as follows:—The slide is bored longitudinally at its upper end to form a seat for, and receive the push-spring, 6, and the sliding plunger, 7, and has a stop-screw, 8, extending transversely through 55 one side thereof, the point of which stop-screw enters a groove, 9, formed in said plunger 7. On the upward movement of the driver its projection 5 strikes the lower end of the plunger 7 which pushes up on the spring 6 and 60 thus lifts the slide S, together with the cap E secured thereto, up against the button-carrier or against the fabric or material laid thereon. In practice, these several parts will be so proportioned and adjusted that the 65 driver will carry a fastener with its point approximately flush with the outer face of the presser-slide before said slide is lifted. This

construction is substantially like the construction shown and described in the Patent No. 381,031 heretofore referred to.

As a means for reciprocating the driver, I employ two parallel vertically reciprocatory and oppositely disposed racks, V and V', respectively, one of which, V, is secured to or formed upon the driver D, and the other V' 75 of which is fixed to a driving-rod, V², journaled in vertical bearings in the frame as shown clearly in Figs. 7 and 8, which driving-rod is reciprocated by a suitable treadle (not shown) through the medium of a connecting-rod, V³, pivotally connected to the treadle and driving-rod. Motion is imparted to the driver D by the driving-rod V² through the medium of a pinion, G, revolvably supported upon a stud, 9', secured to the frame and located intermediate to and with its teeth in mesh with the teeth of the two racks V and V' as shown.

In practice, the rack V upon the driver D, the rack V' upon the driving-rod, and pinion 90 G will be so disposed relative to each other that when the driving-rod-rack is in its elevated position the driver will be in its normal or depressed position, as clearly shown in Fig. 7, and vice versa as shown in Fig. 8. 95

Formed upon the side of the standard 3 of the frame-work, at its front and rear edges, are bearings, 10 and 10', in which bearings are journaled a horizontal shaft, 11, to the front end of which is secured the button-feed 100 wheel F, the construction of which will be hereinafter described. Loosely supported upon said shaft intermediate to said wheel and bearing 10, is a circular die-block B, which die-block is preferably secured to the 105 front face of the said bearing 10 by means of suitable screws, 12, as shown in Figs. 18, 19 and 20, and is grooved upon its under side as at 13, to form the clinching-channel for the fasteners, said groove or channel being directly over 110 and in alignment with the driver-channel 4.

For presenting the buttons to the setting-die in proper position to be attached to the fabric, I employ the button-feed wheel or carrier, F, which is somewhat similar in construction to the feed-wheel described in Patent No. 381,031, referred to. This carrier consists, or may consist, of a disk, 14, having a hub, 14', which is keyed or otherwise secured to the shaft 11. Said feed-wheel F is grooved 120 transversely at its periphery as shown at 15, to form a series of remotely disposed button-receiving seats or carrier-grooves herein shown as six in number and arranged equidistantly around the periphery of said wheel. 125 This wheel F is intended to be intermittently rotated to bring the buttons carried in the grooves 15 thereof successively into vertical alignment with the fastener contained in the driver-channel for and in position to be engaged by said fastener.

As a means for intermittently rotating the feed-wheel to bring the buttons successively into position for attachment to the fabric, I

have provided a pawl-and-ratchet mechanism, designated in a general way by H', which consists of a ratchet-wheel, 16, secured to the feed-wheel shaft 11 and having a series of 5 ratchet teeth corresponding in number to the number of button-carrying grooves 15 formed in the feed-wheel. As a means for rotating said ratchet-wheel, a spring actuated pawl, 17, is provided which is pivoted to a link, 18, 10 loosely mounted upon the shaft 11 at one side of said ratchet-wheel, which pawl engages the teeth of, and partially rotates said ratchet-wheel during oscillation of the link. This link is transversely grooved near one edge 15 thereof as shown at 19, and is oscillated by means, preferably, of a bell-crank, designated in a general way by I, one arm, 20, of which is connected to the link 18 by means of a pin, 21, upon the arm 20 projected into the slot 20 19 in said link. This bell-crank is pivotally supported upon a stud, 22, secured to the frame as clearly shown in the drawings, and has its opposite end, 23, projected through an opening, 24, formed through the web of the 25 channel-shaped upright 3 of the frame and is operatively connected with the driving-rod V² by means of a connecting-rod, 25, pivoted at its upper end to the arm 23 of the bell-crank by means of the stud, 26, and pivoted 30 at its lower end by means of a stud, 27, to a projection, 28, formed upon the sleeve, 29, of the rack V' and extending horizontally through an opening, 30, at the lower end of the upright 3, as clearly shown in Fig. 4 of 35 the drawings.

As shown in the drawings, the sleeve 29 and rack V' will preferably be formed integral and be adjustably secured to the driving-rod V² by means of clamp-screws, 31.

40 In practice, the actuating devices for the driver and feed-wheel will be so constructed and so disposed and timed in their movements that as the driving-rod V² is depressed to elevate the driver D, the link 18 will be retracted from the position shown in Fig. 4, by 45 means of the bell-crank and connecting-rod 25, carrying the pawl over one tooth of the ratchet-wheel into position to partially rotate the ratchet-wheel on the reverse movement of 50 said link, thus leaving the feed-wheel stationary during the clinching operation of the driver D. Upon the descent of the driver D, the movement of the link 18 is reversed from the movement just described, which shifts the 55 ratchet-wheel one tooth, carrying the shaft 11 with it and bringing the next adjacent button in position to be attached to the fabric upon the next ascent of the driver D.

To prevent the accidental retraction of the 60 button-feed wheel during the retractive movement of the pawl and its actuating device, and also to obviate any accidental "overfeed" of said wheel, I have provided an automatic shaft-locking or retaining device, designated 65 in a general way by J. This device consists of a disk or wheel, 32, secured to the shaft 11

near its outer end and having a series of notches, 33, preferably V-shaped formed in its periphery and coinciding in number and position to the lock-notches or grooves formed 70 in the feed-wheel, and a resilient detent-catch, consisting of a spring-arm, 34, secured to the upright 3 of the frame and having a head, 35, adapted to engage the lock-notches in the disk 32 successively as the shaft 11 is rotated 75 to bring the buttons successively into position to be operated upon. The lock-notches will preferably be of V-form so that the head 80 of the detent catch will readily over-ride the faces thereof when force is applied to rotate the shaft 11, but will, in consequence, of the shape of said notches and head, and the force of the spring-arm, bring the shaft with its feed-wheel into proper position, even should the actuating mechanism thereof tend to 85 throw the said shaft too far, and will retain said feed-wheel in a fixed position and prevent movement thereof until force is again applied to its actuating mechanism.

The button-reservoir R, which as herein 90 shown is secured to the upper end of the upright 3, preferably consists of a box-like receptacle having an inclined bottom wall, 36, of semi-circular cross-section and is preferably divided transversely by means of a partition, 95 37, to form two compartments, 38 and 39, the compartment 39 forming the supply-pan, and the one 38 forming the reservoir proper, communication being had between the two compartments through a central recess, 39', formed 100 in the lower portion of the dividing partition 37. Formed through the partition 37 and back wall, 37', of the reservoir are bearings, 40 and 41, respectively, in which bearings is journaled a horizontal shaft, 42, which terminates 105 at its forward end in the front compartment 38 as clearly shown in Fig. 6 of the drawings. Secured to this end of said shaft is a brush-carrying head, 43, having a series of brushes, 44, secured therein as shown in Patent No. 381,031 110 hereinbefore referred to, which brush is adapted to be oscillated as described in said patent to direct the buttons contained in the reservoir to the groove, 45, into the chute H. This chute H, as in the patent referred to, has the 115 usual button-guiding groove, 46, and extends downward and laterally (unless the reservoir be located otherwise than as shown) and terminates adjacent to the setting-die B in the curved part, 46', which conforms to the curvature of the button-carrying wheel.

As a means for oscillating the brush shaft 42 to sweep the buttons into the groove 45 of the reservoir, which groove communicates with the groove 46 of the button-chute, I have 125 provided said shaft at its outer end with a crank-arm 47, (which may be secured thereto by a pin or otherwise or be formed integral therewith) and have connected said crank-arm with the driving-rod V² by means of the 130 connecting-rod, 48, pivoted at its upper end to the crank-arm 47 and at its lower end to the

projection 28 upon the sleeve 29 secured to said driving-rod V², as most clearly shown in Figs. 3 and 4 of the drawings.

By the construction and organization of actuating mechanism as herein described, it will be seen that the driver, button-feed wheel and oscillating brush are all actuated directly from a single driving rod. This construction and organization materially simplifies the machine as compared with the machines known to the art to which this invention appertains, and, in consequence of its simplicity of construction, I am enabled to quickly disassemble and reassemble the parts thereof either for repairs or for the purpose of packing for shipment.

The button-chute H is practically of the same general construction as the button-chute shown and described in Patent No. 381,031 referred to with the exception that instead of one portion thereof being formed integral with the reservoir R, it is constructed in two parts, i.e.—the main body, 50, which is bolted to the frame and has the usual groove 46 in communication with the groove 45 of the reservoir, and the cover, 51, secured thereto by screws, 32, as clearly shown in the drawings. The groove 46, as shown most clearly in Figs. 15, 16 and 17, is a channel formed between two ribs, 53 and 54, of the main body portion 50 of the chute, said channel or groove terminating at its lower end in close proximity to the periphery of the feed-wheel F, and as shown, being tangential to a circle concentric to the axis of said wheel drawn through the center of the button-carrying grooves 15. The rib 53 terminates near the upper face of said wheel, while the rib 54 extends farther downward and backward and terminates in a curved guide or button-guiding finger, 46". As a means for retaining the buttons in the feed-wheel after they leave the chute and until attached to the fabric, I employ a spring guide designated in a general way by L, it consisting, essentially, of a resilient arm, 55, secured to the forwardly projecting bracket of the upright 3 of the frame and having an extension 56 curved as shown in the drawings to lie in front of, and underneath the rim of the feed-wheel F, and having an upwardly projecting curved arm, 57, in alignment with the chute-groove 46 and covering the button-carrying grooves 15 of the feed-wheel at the receiving side thereof, the extension 56 and upwardly projecting arm 57 being preferably curved as shown in the drawings to correspond with the curvature of the feed-wheel, and being integral so that the buttons after they leave the chute and enter the feed-wheel they will be held against accidental displacement during the entire travel thereof, said arm and extension acting to press the buttons backward and upward with their loops closely against the under face of the die-wheel in position to be engaged by the button-fastener in the operation of securing the button to the

fabric, as will be clearly understood by reference to Figs. 7, 8 and 15.

As a means for removably securing the cap E to the upper end of the presser-slide S, I have formed in the front face of said slide contiguous to the front bar 4" of the cap a semi-circular bearing, 58, and adjacent to said bearing 58 I have formed in the inner face of the front bar of the cap E a similar bearing, 59, which bearings are adapted to receive between them a locking-key, 60. This locking-key 60 as shown in the drawings is semi-circular in cross-section at its central portion and has transverse bearings at its ends in the side walls of said cap and is adapted to be turned to unlock the cap from engagement with the presser-slide by means of a lever, 61, connected at its outer end as clearly shown in Figs. 2 and 9.

As a means for normally retaining the key 60 in the locked position shown in Figs. 7 and 8, a spring hook, 62, is provided which is secured at one end to the under face of the front arm of the cap E and bears at its opposite free end against one edge of the semicircular portion of the locking-key 60. When it is desired to remove the cap E from the presser-slide, it is simply necessary to turn the lever 61 downward until the face of the semi-circular portion of the key 60 is vertically aligned with the adjacent faces of the presser-slide and front bar of the cap, this movement of the lever 61 overcoming the resistance of the spring and permitting the cap E to be lifted off from the presser-slide.

As illustrated most clearly in Figs. 2, 3, 6, 9, 10, 11, 12, 13 and 14, the fastener-magazine (designated in a general way by M), is pivotally supported at 63', near its rear end between projecting arms, 63 and 64, formed upon and extending outward from the rear face of the upright 3 of the frame A, the pivotal point of said magazine being preferably in alignment with the right-hand side-face of said upright, said magazine being supported with its forward end in alignment or flush with the rear face of the driver D when said magazine is in its closed operative position as illustrated in Figs. 6, 9 and 10 of the drawings, it being locked in this position by means of a spring-catch, 65, secured at one end to the upper face of the head or vertical projection, 66, of the frame A and having a projection at its free end adapted to engage the magazine when in its operative position, as shown most clearly in Figs. 9 and 10.

The magazine M, which constitutes one of the essential elements of my present invention, consists, essentially, of a main body-portion, 67, (or magazine proper) and an oblong base-portion, 68, to which the magazine is hinged at its sides as shown at 70 and 70' in Figs. 11, 13 and 14, which base-portion 68 has a laterally projecting arm, 68', pivoted between the arms 63 and 64 and forms the pivotal support for the magazine. The main

portion 67 of the magazine is longitudinally grooved at its inner face from end to end as shown clearly in Fig. 13, to form a channel, 67', to receive the T-shaped button-fasteners. 5 This groove is so formed in the magazine that when the portion 67 is closed with relation to the part 68, the prongs of the fasteners will project upward as shown in the drawings.

Extended into the T-shaped slot at the rear end of the magazine is a follower, 73, which is of a shape in cross-section to correspond to the cross-sectional shape of and fit the groove 67', and has at its rear end a handle, 74, by means of which the same may be drawn outward. As a means for normally forcing the follower inward against the fasteners contained in the channel 67', I have provided two pull-springs, 75 and 76, located one at each side of the follower, and secured 15 at one end thereof to projections, 77 and 77', at the forward end of the magazine, and at their rear ends to pins, 77" and 77'", fixed to the rear end of the follower as clearly 20 shown in the drawings. These springs will 25 preferably extend through tubes, 78 and 78', formed upon, or secured to the upper face of the magazine.

As a means for locking the follower in a retracted position to permit re-filling of the magazine, I have provided a spring-actuated 30 detent-catch, 80, at the rear end of said magazine adapted to engage in a notch, 81, in the upper face of the forward end of the follower when said follower is drawn backward as will 35 be clearly understood by reference to Fig. 6 of the drawings.

As a means for preventing the fasteners from dropping out of the magazine during the opening and closing movements thereof, I 40 have provided a cover, 82, which is pivoted to the inner face of the main portion of the magazine at one end thereof as shown in Fig. 13, and is adapted to be opened and closed by a lateral movement thereof to uncover and cover 45 the fastener-receiving channel 67' in said magazine, said cover having a notch, 82', formed in one side near one end to engage the shank of a screw, 82'', underneath the head 50 thereof to hold this end of the cover against accidental displacement as will be clearly understood by reference to said figure.

To prevent the fasteners contained in the magazine from being thrown out by the pressure of the follower when the magazine is 55 swung outward from its normal closed position to the position shown in Fig. 11, I have provided a cut-off which consists of a spring arm, 83, secured at one end to the forward end of the magazine at one side thereof as 60 shown in Fig. 2, and having its free end bent backward as shown at 84, and then at right-angles as shown by dotted lines at 85, in Fig. 9, to form a cut-off plate, 85, which lies closely against the forward end of the magazine and 65 covers the mouth thereof. By bending the arm 83 at its forward end as shown at 84 I form a protecting loop, which, when the maga-

zine is thrown backward to its operative position as shown in said Fig. 9, strikes against a projecting pin, 86, secured in the frame and 70 draws the cut-off plate 85 backward from in front of the fasteners, leaving the channel unobstructed.

To prevent accidental opening movement of the magazine when in its operative position, as shown in Fig. 9, I have provided a pin, 87, which is secured to the upright 3 and extends into a transverse opening formed in the side of the main portion 67 of the magazine when the same is in the position shown 80 in said figure.

Secured to the front end of the reservoir R with its edges preferably flush with the periphery thereof, is a glass plate, T. This plate is removably secured to the reservoir by means 85 of clamps, 88, and clamp-screws, 89, as clearly shown in Figs. 1 and 2. By constructing the plate of sufficient area to entirely cover the front end of the reservoir, the operator is enabled, not only to see the interior of the reservoir, but is also enabled to see the groove 45 which communicates with the chute-channel 46 which is advantageous in that he can at once detect clogging of the groove 45 which might sometimes occur. 95

The general operation of the machine is as follows:—The magazine M and reservoir R being properly supplied and buttons fed down in the chute to the setting-die, the driving-rod V² is operated by the treadle (not shown) 100 which depresses the same, and, through the medium of the pinion G and racks V and V', forces the driver from the position shown in Fig. 7 to the position shown in Fig. 8, which driver engages the head of the foremost fastener, 100, of the series contained in the magazine which is thus driven upward to the upper part of the driver-channel 4. Continuing the upward movement, the projection 5 of the driver strikes the plunger 7, compressing the spring 6 in the presser-slide S, and (during the latter part of the upward stroke of the driver) carries up the presser-slide 110 against the fabric, 102, (previously placed under the feed-wheel and die) and afterward 115 drives upward and sets the fastener as in Figs. 8 and 20, with the fastener prong formed into a hook through the shank 103, of the button, 104. On now lowering the driver as 120 in Fig. 7, the plunger 7 is thrown down until stopped by the screw 8 after which (during the latter part of the downward stroke of the driver) the slide drops by its own gravity to its normal lower position. The driver V² in its 125 upward and downward movements through the medium of the connections hereinbefore described directly operates the oscillating brush in the reservoir and also the feed-mechanism for the feed-wheel F.

By the construction and arrangement of the 130 magazine as hereinbefore described, the operator is enabled to re-fill the magazine without removing the same from the frame, it being simply necessary to swing the same out-

ward as illustrated in Fig. 11, retract the follower, swing the top portion thereof laterally upon its hinges to the position shown in Fig. 13, and swing the cover to one side as shown in said figure, which leaves the channel accessible. After filling the magazine, the cover will be first swung back to its original position, the magazine swung over on its hinges to the position shown in Fig. 11, and the whole 70 swung back to the position shown in Fig. 3, in which position it is automatically locked and is then ready for use.

Having thus described my invention, I claim—

- 15 1. In a button-setting machine, the combination with the frame and with the vertically-reciprocating driver, of a horizontally-disposed fastener-magazine consisting of a base-portion and a longitudinally-grooved fastener-carrying portion hinged to one side of the base-portion and pivotally-supported upon the frame at their ends most remote from the driver and adapted to have a swinging movement at their opposite ends in lines transverse to the line of movement of said driver, a spring-actuated follower supported for sliding movement in the grooved fastener-carrying portion of the magazine, and means for locking the magazine with its delivering-end 85 20 in operative position adjacent to said driver, substantially as described.
- 25 2. In a button-setting machine, the combination with the frame and with the vertically-reciprocating driver and presser-slide, of a magazine pivotally supported at one end and adapted for transverse movement at one end thereof with relation to the presser-slide, and consisting of a base-portion and a longitudinally-grooved fastener-carrying portion 90 30 hinged to one side of the base-portion, substantially as and for the purpose described.
- 35 3. In a button-setting machine, the combination with the frame and with the vertically-reciprocating driver and presser-slide, of a magazine comprising a horizontal base-portion pivotally supported at one end upon the frame, the longitudinally-grooved and channelled fastener-carrying portion hinged to said base-portion at one side thereof, and a cover 100 40 adapted to lie intermediate to the base and fastener-carrying portions of the magazine when the same is closed, and means for automatically feeding the fasteners contained in the magazine, substantially as described 105 45 and for the purpose set forth.
- 50 4. In a button-setting machine, the combination with the frame and with the fastener-driving mechanism, of a longitudinally-grooved fastener-carrying magazine terminating at its delivering end adjacent to the fastener-driving mechanism and pivoted at its opposite end to the frame to have a swinging movement at its delivering end transverse to the plane of movement of the driving-mechanism, and consisting of three members, two 110 55 of which are hinged together to have a transverse opening movement relative to each

other, and the other of which is pivoted at one end between the two aforesaid members so as to have a longitudinal swinging movement with relation to said members, a spring-actuated follower supported for sliding movement within said magazine, and means substantially as described, for locking the magazine in an operative position, substantially as 75 described and for the purpose set forth.

5. In a button-setting machine, the combination with the frame and with the vertically-reciprocating driver, of the fastener-carrying magazine terminating at its delivering end 80 adjacent to the driver and pivotally-supported at its opposite end remote from said driver to have a swinging movement at its delivering end in lines transverse to the line of movement of the driver, a spring catch connected with the frame and adapted for engaging the fastener-magazine to lock the same in its operative position, a spring-actuated follower carried within the magazine, and a detent-catch for locking the follower in its retracted position, substantially as described and for the purpose set forth.

6. In a button-setting machine, the combination with the frame and with the vertically-reciprocating driver, of the horizontally-disposed fastener-magazine pivotally-supported at the end thereof most remote from the driver and adapted to have a swinging movement in lines transverse to the line of movement of said driver, and consisting of the base-portion 68, the longitudinally-grooved fastener-carrying portion 67 hinged to the base-portion at one side thereof, and a cover 82 pivoted at one end to the fastener-carrying portion, a spring-actuated follower supported 100 70 for sliding movement in the longitudinal groove of the fastener-carrying portion of the magazine, means for locking the magazine in its operative position in alignment with the driver with its delivering end adjacent thereto, and a spring actuated detent-catch connected with the fastener-carrying portion 67 and adapted for engagement with the follower to lock the same in its retracted position, substantially as described.

7. In a button-setting machine, the combination with the frame and with the vertically reciprocating presser-slide and fastener-driver, of the horizontally swinging longitudinally-grooved fastener-carrying magazine 110 115 pivotally supported upon the frame, the follower supported for sliding movement in the groove of the magazine, means for locking the magazine in alignment with the driver, means for locking the follower in a retracted position, and means for actuating the follower consisting of pull-springs secured at one end to the magazine and at their opposite ends to the follower, substantially as and for the purpose described.

8. In a button-setting machine, the combination with the frame and with the fastener-driving mechanism, of a fastener-magazine consisting of the two members 67 and 68

hinged together at one side and pivotally supported for horizontal circular movement upon the frame, (one of said members being grooved longitudinally to receive button-fasteners as described) a cover movably secured to the inner face of one of said members, a spring-actuated follower supported for sliding movement intermediate to the one member and its cover, and means for locking said follower in its retracted position, all substantially as and for the purpose described.

9. In a button-setting machine, the combination with the frame and with the vertically reciprocating driver and presser-slide, of the longitudinally-grooved fastener-carrying magazine pivotally supported at one end upon the frame and adapted for transverse movement at one end with relation to the presser-slide and driver, a spring-actuated follower carried in said magazine, and a resilient cut-off plate secured to the magazine at its discharging end, and means for automatically retracting the cut-off plate as the magazine is swung into alignment with the driver, substantially as described.

10. In a button-setting machine, the combination with the frame and with the vertically reciprocating driver and presser-slide, of a pivotally-supported magazine having a longitudinal fastener-receiving groove formed therein from end to end and adapted to be swung away from the driver and presser-slide, substantially as described, a spring-actuated sliding follower carried in the magazine, a spring-actuated cut-off plate secured to the forward end of the magazine in position to cover the discharge-opening therein when the magazine is swung outward with relation to the presser-slide and having a projection or abutment thereon, and an abutment upon the frame located in position to engage the projection upon and retract the cut-off plate when the magazine is swung into its operative position, substantially as described.

11. In a button-setting machine, the combination with the frame and with the vertically reciprocating driver and presser-slide, of the longitudinally-grooved fastener-carrying magazine pivotally supported for horizontal circular movement upon the frame, a spring catch secured to the frame and adapted to engage and lock the magazine in its operative position, a spring cut-off plate secured to the magazine at its forward end and adapted for preventing the discharge of the fasteners contained in said magazine when the same is swung outward with relation to the presser-slide, a spring-actuated follower carried in said magazine, and a detent catch secured to the magazine and adapted to engage and lock the follower in a retracted position, all substantially as described and for the purpose set forth.

12. In a button-setting machine, the combination with the frame and with the vertically reciprocating driver, of the horizontally-disposed fastener-magazine, pivotally-supported

at the end thereof most remote from the driver and adapted to have a swinging movement in lines transverse to the line of movement of said driver, and consisting of the base-portion 68, the longitudinally-grooved fastener-carrying portion 67 hinged at one side thereof, and a cover 82 pivoted at one end to the fastener-carrying portion, and a spring-actuated follower supported for sliding movement in the longitudinal groove of the fastener-carrying portion of the magazine, substantially as described and for the purpose set forth.

13. In a button-setting machine, the combination with the frame and with the vertically reciprocating driver and presser-slide, of the longitudinally-grooved fastener-carrying magazine pivotally supported for horizontal circular movement upon the frame, the fastener-feeding follower sliding in the groove of the magazine, a follower-actuator consisting of two spiral springs located one at either side of the follower in tubes formed upon or secured to the magazine, and secured at their forward ends to the forward end of the magazine, and at their rear ends to the rear end of the follower, and means for locking the follower in a retracted position, substantially as described and for the purpose set forth.

14. In a button-setting machine, the combination with the frame and reciprocating driver and with the fastener-magazine pivotally-supported thereon with its delivering end adjacent to the driver, of the vertically reciprocating presser-slide S, the cap removably-secured thereto and overlapping the delivering end of the fastener-magazine, and means for locking said cap to the presser-slide consisting of a key revolvably-supported in contiguous semi-circular grooves formed in the adjacent faces of the cap and slide, and a spring bearing against said key to hold the same with portions thereof in engagement with the cap and slide, substantially as described.

15. In a button-setting machine, the combination with the reciprocating driving-rod journaled in the frame, the pinion rotated by said rod and the driver actuated by the pinion, of the horizontal button-feed-wheel shaft in axial alignment with the magazine when in its operative position, and means for intermittently rotating said shaft consisting of a ratchet-wheel secured thereto, an oscillating link loosely mounted upon the shaft and carrying a spring-actuated pawl adapted to engage the teeth of the ratchet-wheel, a lever engaging said link, a connecting-rod pivoted to said lever and directly connected with a sleeve shiftably secured to the driving-rod, and means for actuating the driving-rod, substantially as described and for the purpose set forth.

16. In a button-setting machine, the combination with the frame and with the vertically reciprocating driver having a toothed rack at its lower end, of the vertically-reciprocating driving-rod pivotally supported at its ends in

the frame, and having the rack thereon, the pinion pivotally supported between, and in mesh with the teeth of the driver and driving-rod, the horizontally-disposed feed-wheel shaft located in parallelism with the magazine and having the feed-wheel F secured thereto, the pawl-and-ratchet mechanism connected therewith, and the bell-crank or ratchet-operating lever pivotally supported upon the frame in direct vertical alignment

with the driving-rod and directly connected with said driving-rod by means of a connecting-rod pivoted at its upper end to one end of the bell-crank and at its lower end to a shiftable projection upon said driving-rod, substantially as and for the purpose set forth. 15
